TRAVELING BLOCK

Erwin Burns, Los Angeles, and Harry P. Wicker-sham, Huntington Park, Calif.

Application August 7, 1935, Serial No. 35,106

12 Claims. (Cl. 254—192)

This invention relates to hoisting apparatus and relates more particularly to a sheave block or traveling block. A general object of this invention is to provide a sheave block or traveling block that is dependable and effective in use and that is particularly simple and inexpensive of manufacture.

The present invention is concerned with a sheave block adapted for use in conjunction with the hoisting apparatus of a well derrick, it being understood that the block of the invention is well adapted for use in other situations and that the references herein to its employment in a well derrick are not to be construed as limitations to the application of the invention.

The traveling sheave blocks in general and particularly the class of traveling blocks used with the hoisting apparatus of a well derrick usually embody a great number of separable parts. In the typical forms of traveling blocks the plates between the sheaves, the side plates or cheeks, the spacers between the plates, etc., are separate parts and are held assembled by bolts, nuts, tie-rods, etc. An assembly of such a large number of parts is expensive and has the serious objection of not being rigid. It is a rather common practice to employ the sheave supporting shaft and the bail supporting pin as elements for holding the assembly together. This arrangement makes the block bulky and very thick as the nuts or other securing parts on the shaft and pin form hazardous projections at the opposite sides of the block. Further, where the bail pin is employed as a connecting member of the general assembly its removal for the application of an elevator, hook or the like, is a difficult operation and its removal and replacement at the well derrick often result in an improper assembly and adjustment of the block.

Another object of this invention is to provide a traveling block that is extremely simple in construction embodying a minimum number of parts.

Another object of this invention is to provide a traveling block that is very sturdy and therefore safe and dependable in operation. The various parts of the block of this invention are utilized to the best advantage to provide a strong rugged assembly and the body or frame is rigid without employing the sheave supporting shaft, the bail pin or any other working parts as structural connecting elements.

Another object of this invention is to provide a traveling block that is compact and without pro-

jecting parts that might interfere with the lines or other apparatus.

Another object of this invention is to provide a sheave block or traveling block in which the pin carrying the clevis or bail may be easily and quickly removed and replaced to facilitate the connection of an elevator, hook or the like with the block without disturbing any other parts of the block.

Another object of this invention is to provide a traveling block that is narrow or of minimum width, the main shaft being devoid of nuts or the like and the block being without other parts that widen or necessitate widening of the assembly.

Another object of this invention is to provide a traveling block of the character mentioned that is very inexpensive, embodying a minimum number of parts that require only simple machining and finishing.

A further object of this invention is to provide a traveling block that embodies a frame or body formed of only two sections that have integral partitions or spacers for spacing the sheaves and for cooperating with the shaft to support the shaft at longitudinally spaced points and strengthen and lend rigidity to the assembly.

The various objects and features of our invention will be fully understood from the following detailed description of a typical preferred form and application of the invention, throughout which description reference is made to the accompanying drawings, in which:

Fig. 1 is a front elevation of the block provided by this invention. Fig. 2 is a side elevation of the block. Fig. 3 is an enlarged vertical detailed sectional view taken as indicated by line 3—3 on Fig. 1 and Fig. 4 is an enlarged vertical detailed sectional view taken as indicated by line 4—4 on Fig. 2.

The improved traveling block of this invention includes, generally, a frame or body 10, a pin or shaft 11, sheaves 12 on the shaft 11 and means 13 for suspending a hook, elevator or other hoisting device from the body 10.

The frame or body 10 carries the various other elements of the block and is adapted to be operated on or suspended from a line or cable. The construction and formation of the body 10 is an important feature of the present invention. In accordance with the invention the frame or body 10 comprises or consists of two sections 14. The sections 14 are alike or identical and are adapted to be fitted together or assembled to constitute a housing or shell for enclosing and carrying the

55

shaft 11, the sheaves 12, etc. The body sections 14 are integral parts or castings of cast steel or the like and each comprises spaced sides 15 and an outer wall 16. The sides 15 constitute the cheeks 5 of the block when the sections 14 are assembled and the major intermediate portions of the sides 15 are vertical and parallel.

The upper portions of the side walls or sides 15 taper or converge upwardly rather abruptly 10 while the lower portions of the sides 15 converge downwardly at a less abrupt angle. The outer wall 16 of each body section 14 is inclined in opposite directions from a substantially central horizontal plane whereby the upper and lower 15 portions of the walls 16 of the two body sections 14 are respectively upwardly and downwardly convergent as clearly illustrated in Figs. 1 and 4 of the drawings. The sides 15 and the walls 16 of the assembled body sections 14 constitute a 20 closed structure enclosing or providing a chamber for carrying one or more sheaves 12.

In accordance with the invention partitions or 25 spacers 17 extend through the interior of the body 10 to provide a plurality of compartments 18. It is a feature of the invention that the dividing plates or spacers 17 are integral parts of their respective body sections 14. Each body section 14 has a plurality of spaced vertical or parallel spacers 17 projecting from its wall 16 in parallelism with the sides 15. Where the 30 sheaves 12 are of uniform size as shown in the drawings the spacers 17 are equally spaced to provide compartments 18 of equal width. The spacers 17 of the two connected opposing body 35 sections 14 are in direct alignment or in common vertical planes. The number of aligned spacers 17 and, therefore, the number of compartments 18, depends upon the number of sheaves 12 embodied in the block. In the particular embodiment of the invention shown in the drawings there are four parallel spacers 17 on each section 14, the spacers of the two sections dividing the interior of the body 10 into five equal compartments 18, each adapted to receive or contain a 40 sheave 12.

The upper ends of the spacers 17 terminate at or join substantially horizontal walls or partitions 19. The spacers 17 are integrally joined with and extend upwardly from substantially 45 horizontal walls or partitions 20. The lower partitions 20 are somewhat thicker and deeper than the upper partitions 19. The inner edges of the sides 15, the spacers 17 and the upper and lower wall portions of the walls 16 of the two sections 50 14 are vertical. The partitions 19 and 20 continue beyond the edges of the sides 15 and the spacers 17 to project slightly and present finished vertical surfaces 21. The surfaces 21 of the two sections 14 are adapted to cooperate or 55 abut. The surfaces 21 preferably extend throughout the width of the body 10 to provide ample bearing or cooperation between the two body sections 14. It is to be noted that the two surfaces 21 of each body section 14 may be inexpensively accurately machined to insure the proper mating and assembling of the body sections.

Rows of spaced depressions or recesses 22 are 60 provided in the walls 16 in alignment with the compartments 18 and adjacent the partition 19. The portions of the walls 16 forming the bottom or inner walls of these recesses 22 are thickened and substantially normal to the upper partitions 19. Similar spaced depressions or recesses 24 are 65 provided in the outer walls 16 adjacent the lower

partitions 20. The portions of the walls 16 constituting the bottoms of the recesses are thickened and substantially normal to the partitions 20. Horizontal openings 25 are provided in the inner or bottom walls of the recesses 22 and 24 5 and pass or receive securing members 26. In the typical preferred form of the invention shown in the drawings the securing members 26 for connecting the two body sections 14 are in the form of tie rods and nuts 27 are threaded on the 10 end portions of the tie rods 26 to bear on or engage finished surfaces 28 surrounding the openings 25. The nuts 27 threaded on the tie rods 26 and engaging the surfaces 28 securely connect the sections 14 of the body with the surfaces 21 15 of the body sections in abutment. The number and spacing of the tie rods 26 is such that the sections are very rigidly held together against working or shifting relative to one another. It is to be noted that the tie rods 26 and the nuts 27 are provided solely for connecting the body 20 sections 14 together and do not serve any other functions. Set screws 29 are threaded through 25 openings in outer walls 30 of the recesses 22 and 24 to engage the flat sides of the nuts 27 for the purpose of preventing unthreading of the nuts. The outer walls 16 of the body sections 14 are recessed at 30 to receive the heads of the set screws 29 so that the screws do not project from the body 10. 30

The tapering or convergent portions of the body sections 14 above the partitions 19 have vertically elongated openings registering to form an opening 31 to receive a line or cable for suspending and operating the block. Ribs or rims 32 may surround the opening 31 at the inner surfaces of the sections 14. The lower portion of the body 10, that is the portions of the sections 14 below the partition 20, is formed to carry the means 13. The lower end of each body section 40 14 has a plurality of downwardly projecting webs or flanges. These flanges are vertical or parallel and the flanges of one section 14 mesh with the flanges of the other section. In the case illustrated in the drawings each body section 45 14 has four flanges, one flange 34 immediately adjacent and at one side of the vertical central plane of the block, two outer flanges 35 and 36 and a flange 37 spaced from the inner flange 34 at the other side of the central vertical plane. 50 The flanges 34, 35, 36 and 37 project inwardly from the inner edges of the body sections 14 and are provided with curved or rounded edges. The flanges 34, 35, and 36 of the two body sections 14 are positioned and related to mesh or 55 overlap as clearly shown in Fig. 3 of the drawings. Slots or openings 39 are provided in the outer walls 16 in a plane above the shaft 11 and in central alignment with the compartments 18 to freely pass the cables or lines operating over 60 the sheaves 12. Similar slots 39^a are provided in the walls 16 to facilitate the threading of the line or lines through the block.

The pin or shaft 11 extends through and is carried by the body 10 to rotatably support the 65 sheaves 12. The shaft 11 extends transversely or horizontally through the body 10 at or adjacent its central horizontal plane. In accordance with the invention aligned partially or semi-cylindrical openings or notches 40 are provided 70 in the inner opposing edges of the sides 15 and the spacers 17 of the two body sections and register to form openings which receive the shaft 11. The partitions or spacers 17 are thickened around their notches 40 and their thickened portions are 75

faced or machined to have finished thrust surfaces 41. Bosses 42 are provided on the outer surfaces of the sides 15 and have recesses 43. Relatively small heads 44 are provided on the 5 opposite ends of the shaft 11 and are countersunk or received in the recesses 43 to be flush with or inset from the outer surfaces of the bosses 42.

In accordance with the invention the sheave supporting shaft 11 has a plurality of enlarged 10 cylindrical bearing portions 45 for carrying or supporting the sheaves for rotation in spaced parallel planes. The bearing portions 45 are spaced apart longitudinally of the shaft 11 leaving annular grooves 46. The spacers 17 extend 15 into or cooperate with the grooves 46. The finished faces 41 of the thickened portions of the spacers 17 are adapted to engage or bear on the side walls of the groove 46 while the walls of the notches 40 in the spacers are adapted to co-operate with the bottom or inner walls of the grooves. Grooves 47 are provided in the shaft 11 between the heads 44 and the outermost bearing portions 45 to receive the flanges 48 on the sides 15. It is to be noted that the spacers 17 20 and the sides 15 cooperating with or extending 25 into the grooves 46 and 47 just described effectively support the shaft 11 at longitudinally spaced points or planes. The cooperation of the spacers 17 and the sides 15 with the grooves 46 30 and 47 positively holds the shaft 11 against longitudinal movement and materially braces the entire assembly.

The sheaves 12 carry the lines or cables employed in the drilling and operating of the well. 35 The several sheaves 12 may be identical and of the same effective diameter, it being understood that the sheaves may be of different effective diameters, if desired. A sheave 12 is provided in each compartment 18 and is supported for 40 independent rotation on the shaft 11. Each sheave 12 may include a thickened hub 50 having flat normal ends, webs or bodies 51 and rims 52. Grooves 53 are provided in the rims 52 to carry the line or lines. Anti-friction bearings 45 54 are provided to support the sheaves 12 for rotation on the bearing portions 45 of the shaft 11. The sheaves 12 have suitable operating clearance in the compartments 18 and the lines from the sheaves are adapted to freely pass 50 through the openings 39. A plurality of longitudinal lubricant ports 56 is provided in the shaft 11. A port 56 is provided for conducting lubricant to each individual bearing 54 whereby the individual bearings and the individual pulleys or sheaves 12 may be properly lubricated. Lubricant receiving fittings 57 may be provided 55 at the outer ends of the ports 56.

The means 13 for suspending a device or part of the hoist equipment from the block body 10 60 includes a clevis or bail 60. The bail 60 is substantially U-shaped in side or edge elevation having spaced arms 61. The arms 61 are adapted to extend upwardly between the pairs of spaced flanges 36 and 37. The flanges 34, 35, 36 and 37 65 have horizontally aligned openings 62 and the arms 61 of the bail have horizontal openings 63 adapted to be aligned with the openings 62. A pin 64 is arranged through the openings 62 and 63 to pivotally connect the bail 13 with the block body 10. The pivot pin 64 is adapted to be inserted and engaged through openings 65 formed by aligned or opposing notches in the edges or sides 15. The pin 64 is readily removable to permit the detachment of the bail 13 from the block 70 body 10. The hook, elevator or the like may be 75

readily connected with the block by the bail. A head 66 is provided on one end of the pivot pin 64 to cooperate with the outer side of a flange 35. The other end portion of the pin 64 is reduced in diameter and threaded to receive a nut 67 for 5 cooperating with a flange 36. A cotter key 68 may be arranged through a transverse opening in the pivot pin 64 to prevent accidental displacement of the nut 67. It is to be noted that the lower portions of the sides 15 are spaced outwardly from the head 66 and the nut 67 and form shields or hoods at the opposite ends of the pivot pin 64. The lower portion of the bail 60 projects from the lower end of the body 10 and forms a loop for receiving or engaging the eye or bail of a 15 piece of hoist equipment. Stops or wings 69 may be provided on the arms 61 of the bail 60.

It is believed that the utility and practicability of the sheave block or traveling block of this invention will be apparent from the foregoing detailed description. The block embodies a minimum number of simple, sturdy parts comprising only five major parts or elements, namely the body 10, the shaft 11, the sheaves 12, the bail 60 and the bail pin 64. The body 10 comprising the two complementary sections 14 is definitely and effectively held assembled by the multiplicity of tie bolts 26. The rows of tie bolts 26 with the nuts 27 threaded on them hold the two sections 14 together so that their surfaces 21 are in tight 30 abutment. The sheave carrying shaft 11 is dependably supported at longitudinally spaced points or planes by the cooperation of the sides 15 and spacers 17 with the grooves 47 and 46. The spacers 17 extend through the interior of the body 35 to properly space the individual sheaves 12 to support the shaft 11 between its ends and strengthen and lend rigidity to the assembly. The sheaves 12 supported on the bearing portions 45 of the shaft 11 through the lubricated bearings 54 are effectively carried for free rotation. The clevis or bail 60 is removably pivotally connected with the body 10 by the pivot pin 64 in a manner so that it may be removed from and re-attached to the body without disturbing any other 45 parts of the assembly. The pivot pin 64 is provided solely for the purpose of carrying the clevis 60 and its removal in no way affects the mounting of the sheaves or the connection between the body sections 14. The pin 64 may be easily removed 50 to permit the detachment of the clevis 60 and may be easily reinserted in the openings 62 and 63 and retained in place by the nut 67 and cotter pin 68 to again secure the bail to the body 10. It is to be particularly noted that the block of the 55 present invention is of minimum thickness and does not have any projecting parts such as nuts, bolt heads, or the like. The shaft 11 is not employed as a means for connecting the assembly and therefore does not have any nuts or securing 60 members on its ends to thicken the assembly or project from the sides of the block. The various parts embodied in the block are very simple and require a minimum of finishing and machining.

Having described only a typical preferred form 65 and application of our invention, we do not wish to be limited or restricted to the specific details herein set forth, but wish to reserve to ourselves any variations or modifications that may appear to those skilled in the art or fall within the scope 70 of the following claims.

Having described our invention, we claim:

1. A sheave block including, two unitary body sections each having spaced internal spacers, there being notches in the edges of the spacers,

- means connecting the sections so that their spacers are aligned to form compartments and said notches are in registration to form openings, a shaft carried in the openings, and sheaves in the compartments rotatably carried by the shaft.
2. A sheave block including two body sections each having spaced internal spacers, means connecting the sections with their spacers aligned and in substantially edge to edge relation to form compartments, a shaft carried by the sections, and sheaves in the compartments rotatable on the shaft.
3. A sheave block including, two frame sections each section comprising spaced partition parts, a shaft having longitudinally spaced grooves, means securing the frame sections together with their partition parts in alignment and cooperating with the grooves, and sheaves in the compartments rotatable on the portions of the shaft between the grooves.
4. In a sheave block, body sections each comprising sides and spacers between the sides, means connecting the sections so that their sides and spacers are substantially aligned, a shaft supported by the sides and spacers of the sections, and sheaves on the shaft spaced one from the other by the spacers.
5. In a sheave block, two integral body sections each comprising spaced sides and spaced partition parts between the sides, means connecting the sections with their partition parts in substantially edge to edge opposition, there being notches in the opposing edges of the said parts of the sections aligned to form openings, a shaft carried in the openings, and sheaves rotatably supported on the shaft between said parts.
6. In a sheave block, two integral body sections each comprising spaced sides, means connecting the sections with their sides in substantially edge to edge opposition, a shaft extending between the sides, a sheave rotatable on the shaft, and parts on the sections supporting the shaft at points between its ends.
7. In a sheave block, two integral body sections each comprising spaced sides, means connecting the sections with their sides in substantially edge to edge relation, a shaft extending transversely between said sides, a plurality of sheaves on the shaft, and means on each section supporting the shaft at longitudinally spaced points and spacing the sheaves.
8. In a sheave block, two body sections each comprising spaced sides, means connecting the sections with their sides in substantially edge to edge relations, a shaft extending transversely between said sides, a plurality of sheaves on the shaft, and means supporting the shaft at longitudinally spaced points and spacing the sheaves, the last mentioned means including spacers on the sections extending between the sheaves and cooperating with the shaft.
9. A line handling device including a body divided into two like complementary sections, means rigidly connecting the sections, a shaft having its longitudinal axis substantially in the plane of division of the body, the said sections each including spaced internal partition parts supporting the shaft at longitudinally spaced points, and sheaves rotatable on the shaft in the spaces between said parts.
10. A line handling device including a body divided longitudinally into two sections, tie rods connecting the sections, a shaft having its longitudinal axis substantially in the plane of division of the body and supported by the sections, a rotatable sheave on the shaft, a bail, and means connecting the bail with the body for removal therefrom without disturbing the sections, rods or shaft.
11. A line handling device including a body divided longitudinally into two sections, tie rods connecting the sections, a shaft having its longitudinal axis substantially in the plane of division of the body and supported by the sections, a rotatable sheave on the shaft, the sections including overlapping parts having aligned openings, a removable pin carried in the openings, and a bail pivotally carried by the pin.
12. A line handling device including a body divided longitudinally into two sections, tie rods connecting the sections, a shaft having its longitudinal axis substantially in the plane of division of the body and having longitudinally spaced grooves, the sections including parts cooperating with the grooves, and sheaves rotatable on the portions of the shaft between the grooves.

HARRY P. WICKERSHAM.
